UNITED STATES PATENT OFFICE.

ALBERT VICTOR PAUL, OF LAMBHILL, GLASGOW, SCOTLAND.

MAKING-READY PROCESS.

1,111,611.

Specification of Letters Patent. Patented Sept. 22, 1914.

Application filed January 20, 1914. Serial No. 813,293.

To all whom it may concern.

Be it known that I, ALBERT VICTOR PAUL, a subject of the King of England, residing at 3 Hillend road, Lambhill, Glasgow, Scotland, have invented certain new and useful Improvements in Making-Ready Processes, of which the following is a specification.

This invention relates to letter-press printing by means of stereotype or other plates or their equivalent as used on rotary and on flat bed machines, and has for its object to provide for the more ready and effective leveling or making ready of the printing surfaces of such plates or the like in order 10 to obtain a uniform printed impression therefrom, free from the occurrence of heavy and light parts due to that variation in the level of the type which is found in the cast plates or their equivalent.

20 The invention comprises the hereinafter described improved process of effecting the aforesaid leveling or making ready of the printing plates or the like.

According to the present ordinary method 25 of making ready, the type plate is mounted on the printing machine and a first impression printed therefrom. The paper with such impression thereon is then examined and in places corresponding with the parts 30 where the impression or printing is very light, pieces of paper are pasted and underlaying or overlaying as it is termed, according as to whether the paper is inserted beneath the printing plate or upon or adjacent to the rotary or flat impression surface, is repeated until a uniform impression 35 is obtained. It has been proposed to produce making ready pieces from plastic materials molded or cast so as to have the required contour. A further proposal involves the use of chemical means for treating 40 the making ready piece.

In making ready, in accordance with this invention, I mount the type plates, if intended for use in a rotary printing machine, upon a cylinder of the same diameter as the cylinder of the machine on which they will be subsequently mounted for service. The surface of the type is then coated with 45 ink, after which a sheet of stout paper, or other suitable material, is tightly stretched over the said surface and secured thereon. The cylinder is now rotated and during such

rotation the surface of the aforesaid paper, or its equivalent, is caused to contact with a 55 revolving emery wheel, or other suitable abrasive, with the result that at those parts where the type beneath it is high the paper will be ground away and there will be produced a sheet of varying thickness, the variation 60 corresponding with the variation or irregularity in the level of the type.

The accompanying drawing gives a diagrammatic illustration of the grinding operation aforesaid.

65 The type plate or its equivalent *a* is mounted on the cylinder or the like *b*, and over the outer surface of the type or printing face of *a* there is placed the sheet of stout paper or its equivalent *c*, which is to 70 form the making-ready piece as hereinafter described. The grooves or recesses *d* give an exaggerated indication of the variation in the level of the printing face of the plate *a*. The emery wheel or abrasive is represented by *e*. On setting *b* and *e* in rotation and bringing the latter and the making ready piece *c* (which is rotated with *b*) into contact, the parts of *c* which have the high or projecting portions of the type plate *a* 75 beneath them will be ground down, while the parts of *c* having the depressed portions of *a* (represented by the recesses *d*) beneath them will yield and so escape grinding.

80 The aforesaid grinding or thinning of the paper may be effected in various ways and with various material and either by hand or power. In some cases the surface of the making ready piece may be simply rubbed over the abrasive surface or vice-versa. 85 After the conclusion of such grinding or rubbing down operation, the sheet of paper or other material is stripped off and the type plate or plates or their equivalent mounted on the cylinder of the machine on which the 90 printing is to be done. A sheet of clean paper is now wound around the blanket cylinder of the machine and an impression printed thereon. The aforesaid sheet of ground down material or making ready 95 piece, is then fastened around the blanket cylinder, with its ground surface inmost and in such a position that the printed impression made on it during the grinding process is in perfect register with the impression 100 on the blanket cylinder, or the paper there-

on. The variations in the thickness of the making ready piece are thus made to correspond exactly with the variations in the level of the face or surface of the type, 5 and to compensate for the same with the result that a perfectly uniform impression can now be printed.

By my improved process of making ready, the printing machine can be prepared and 10 started to work in a very expeditious and convenient manner.

The invention is applicable for printing with machines of various kinds, either rotary or flat bed. The making ready piece 15 may be applied either as an overlay, as hereinbefore described, on the blanket cylinder or its equivalent, or as an underlay beneath the printing plates or their equivalent, or two making ready pieces may be employed, 20 the underlay piece being prepared and placed in position before the overlay piece is prepared. This double making ready will not as a rule be necessary, but may be adopted with a very irregular printing plate.

25 Having now particularly described and ascertained the nature of my said invention

and in what manner the same is to be performed, I declare that what I claim is:—

1. The herein described process which consists of grinding the making ready piece 30 while it is in contact with the printing surface whereby is produced a sheet of varying thickness, substantially as and for the purpose set forth.

2. The herein described process which 35 consists of grinding away portions of the making ready piece to compensate for variations in the level of the printing surface whereby there is produced a sheet of varying thickness, substantially as described.

3. The herein described process which 40 consists in placing the making ready piece in contact with the printing surface and grinding those portions over the high parts of the type plate, the portions over the low 45 parts yielding.

In testimony whereof, I affix my signature in presence of two witnesses.

ALBERT VICTOR PAUL.
